(57) **CLAIM**

The ornamental design for a electric cable cutter, as shown and described.

DESCRIPTION

FIG. 1 is a front elevational view of the electric cable cutter, showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view taken from the front, top and right side of the electric cable cutter; and,

FIG. 8 is a perspective view taken from the rear, top and left side of the electric cable cutter.

The elements shown in broken lines are for illustrative purpose only and form no part of the claimed design.
